UNITED STATES PATENT OFFICE.

HEINRICH ZOELLY, OF ZURICH, SWITZERLAND, ASSIGNOR TO ESCHER, WYSS & CO., A CORPORATION OF SWITZERLAND.

SHIP PROPULSION.

1,158,617.

Specification of Letters Patent. Patented Nov. 2, 1915.

Application filed May 26, 1914. Serial No. 840,972.

To all whom it may concern:

Be it known that I, HEINRICH ZOELLY, a citizen of the Republic of Switzerland, residing at Zurich, in the Republic of Switzerland, have invented certain new and useful Improvements in Ship Propulsion, of which the following is a full, clear, and exact specification.

This invention relates to a driving arrangement for screw-propelled ships provided with at least three shafts and driven by steam and electric power.

The invention resides in the fact that at least two shafts are driven solely by steam turbines and that the other shaft or shafts are driven solely by electromotors in which action the electromotor or electromotors is or are fed from at least one turbo-dynamo, the arrangement being such that in the case of cruising speed the electrically driven shaft or shafts perform the main work and the waste steam from the auxiliary turbines driving the dynamos is caused to enter always a high pressure stage of the propeller steam turbines, whereas in the case of full-speed the steam-propelled shafts perform the main work.

It has already been proposed to provide driving means for screw-propelled ships in which both steam and electric power are simultaneously employed. In this known case, however, the arrangement is such that a steam turbine as well as an electromotor are mounted on one and the same shaft. This circumstance necessitates a very expensive and what is more important a very heavy engine plant which on account of its great polar momentum of inertia of the rotating masses renders its control extremely difficult. Now according to this invention the above great drawback is obviated without dispensing with the known and great advantages of the combined working.

The accompanying drawing illustrates diagrammatically and by way of example a manner of carrying the invention into effect.

Journalized in the ship's hull are two inner shafts 1 and 2 and two outer shafts 3 and 4. The two inner shafts 1 and 2 are more particularly arranged for cruising speed and are driven by electromotors 5 and 6, which receive their current from a dynamo 8 which is driven by a high speed auxiliary steam turbine 7. The two outer shafts 3 and 4 are

principally destined for full speed and are driven by large steam turbines 9 and 10. The turbines may in the usual manner be also coupled with reversing turbines. If it is desired to drive the ship for a long time at a slow speed, the two inner shafts 1 and 2 are used to perform the principal work required. In order, however, that the propellers on the two outer shafts 3 and 4 are not merely dragged along whereby as experience has shown a very high resistance would be produced the steam conduit is so arranged that the auxiliary turbine 7 driven by fresh steam delivers its exhaust to the two large turbines 9 and 10 in causing it to enter each turbine into a pressure stage which is close to the inlet of the live steam, for instance, at 11 in the turbine 9 and at 12 in the turbine 10. The steam then continues to operate in these large turbines 9 and 10 which are thus connected in parallel until it reaches condenser pressure and it drives the outer shafts 3 and 4 in the same sense of the ship's movement in which the electromotors 5 and 6 drive the shafts 1 and 2. Now if the ship is run at a higher speed, live steam is supplied to the turbines 9 and 10 in a known manner in which it is caused to expand to condenser pressure and in this action gives off a great amount of work to the outer shafts 3 and 4 so that the latter are caused to rotate at an increased speed. Now in order that the propellers on the inner shafts 1 and 2 are not merely dragged along but that they should aid the two outer shafts the motors on shafts 1 and 2 are to be driven at a higher speed. This can be done either by increasing the speed of the auxiliary turbine 7, or by changing the pole connections on the dynamo 8 (or on the motors 5 and 6) in order to increase the periodicity of the current produced, and thereby the revolutions of the motors 5 and 6 if alternating current is used, or by changing the electric resistances should the current be continuous. The electromotors 5 and 6 rotating more rapidly are thereby aiding the steam turbines 9 and 10 in the delivery of their energy to the ship. The steam used up by the auxiliary turbine 7 is now introduced into lower stages of the turbines 9 and 10, say at 13 and 14 respectively, so that it may continue its work in the lower stages of the main turbines. If 8 is a continuous current dynamo and should it be desired to drive it at a lower speed

a reduction gear may be fitted between turbine 7 and dynamo 8.

The low or cruising speed shafts 1 and 2 are preferably symmetrically arranged relatively to the axis or center line of the ship. If only one is used, it would preferably be located axially in the ship.

It will be seen that a ship equipped with three or more propellers driven according to this invention will have a wide range of speeds and maneuvering ability, and will be very economical for cruising.

The invention is specially advantageous for ships of war, which are seldom required to travel at maximum speed, but which must have ample provision therefor, as well as for handling in maneuvers.

While I have not shown herein the boiler, piping and valves for directly supplying the turbines 9 and 10 with high pressure steam, nor the various steam and electrical controlling appliances, nor the condensers, such appliances will be well understood and applied without further description or illustration, and are unnecessary to a full understanding of this invention. The controls will preferably be capable of driving some or all propellers in the same or reverse directions, so as to give ample opportunity for turning, etc., in evolutions.

Various modifications and changes may be made without departing from the scope of the appended claims.

Having thus described my invention, I declare that what I claim as new and desire to secure by Letters Patent, is:—

1. The combination of at least three propeller shafts, means for driving certain of said shafts solely by steam to obtain one speed of propulsion, and means for driving the remaining shafts solely by electric motors to obtain another speed of propulsion.

2. The combination of at least three propeller shafts, steam driving means alone for certain of said shafts furnishing the main driving power at one speed, and electrical driving means alone for the remaining shafts furnishing the main driving power at a lesser speed.

3. The combination of at least three propeller shafts, steam driving means alone for two of said shafts, electric motors alone for driving the remaining shafts, an independent high speed turbo-dynamo set generating current for said motors, and means for preventing dragging of the idle shafts when the other shafts are developing power.

4. The combination of at least three propeller shafts, steam driving means alone for two of said shafts, electric motors alone for driving the remaining shafts, an independent high speed turbo-dynamo set generating

current for said motors, and means for exhausting the steam from the high speed dynamo turbine into the steam driving means of the steam driven propeller shafts.

5. In combination with a ship having two sets of propellers, turbine means for directly driving one set, and turbo-electric means for driving the other set, and means preventing dragging of the idle set when the other set is developing propulsion power.

6. In combination with a ship, electrically driven propeller shafts for cruising speed, a dynamo turbine furnishing power for said electrically driven propeller shafts, direct steam driven propeller shafts for full speed, and means for supplying the direct steam driving means with exhaust steam from the dynamo turbine.

7. In combination with a ship, a turbine and direct connected dynamo, a propeller shaft, an electric motor connected to said dynamo for driving said shaft, a second propeller and shaft a direct driving turbine therefor, and means for supplying exhaust steam from said dynamo turbine to turn over said direct turbine.

8. In combination with a ship, a dynamo turbine and direct connected dynamo, a propeller shaft, an electric motor connected to said dynamo for driving said shaft, a second propeller and shaft, a direct driving turbine therefor, means for supplying exhaust steam from said dynamo turbine to turn over said direct turbine, and means for supplying high pressure steam to said direct turbine at another point.

9. In combination with a ship, a dynamo turbine and direct connected dynamo, a propeller shaft, an electric motor connected to said dynamo for driving said shaft, a second propeller and shaft, a direct driving multi-stage turbine therefor, and means for supplying exhaust steam from said dynamo turbine to an intermediate stage of said direct driving turbine.

10. In combination with a ship, a dynamo turbine and direct connected dynamo, a propeller shaft, an electric motor connected to said dynamo for driving said shaft, a second propeller shaft and a multi-stage propeller turbine, direct connected thereto, means for delivering exhaust steam from said dynamo turbine to a higher pressure stage of said propeller turbine when the ship is running at cruising speed than when running at full speed.

In testimony whereof I affix my signature, in presence of two witnesses.

HEINRICH ZOELLY.
